UNITED STATES PATENT OFFICE.

GEORGE M. PORTEOUS AND FREDERICK S. MILLER, OF CHICAGO, ILLINOIS.

DESIGN FOR A PHOTOGRAPH-EXHIBITOR CASE.

SPECIFICATION forming part of Design No. 18,853, dated January 8, 1889.

Application filed November 5, 1888. Serial No. 290,063. Term of patent 7 years.

To all whom it may concern:

Be it known that we, GEORGE M. PORTEOUS, a citizen of the United States, and FREDERICK S. MILLER, a subject of the Queen of Great Britain, both residing at Chicago, in the county of Cook and State of Illinois, have invented and produced a new and original Design for a Photograph-Exhibitor Case, of which the following is a specification, reference being had to the accompanying drawings, forming part thereof.

In said drawings, Figure 1 is a perspective view of a photograph-exhibitor case showing our design. Fig. 2 represents the same in front elevation, and Fig. 3 is a top plan view thereof.

The leading feature of our design consists in a photograph-exhibitor case having a substantially half-oval-shaped body and a cover provided with representations of moldings which rise in height from the edge toward the center of the cover, substantially as herein shown and set forth.

In said drawings, A represents the body of the case, and B the top or lid thereof. The body of the case has a flat front side, a , and a corresponding rear side, a' , which latter will be readily understood by reference to the front side. The outline of each of said two sides of the case is substantially a half-oval or semi-ellipse. The middle portion, a^2 , of the body of the case forms what may be regarded as its bottom and end portions, and is a whole curved in conformity to the substantially half-oval outlines of the front and

rear sides, a and a' , of the body of the case, which said outlines are met by the edges of the said substantially half-oval middle portion, a^2 , of the case.

The top surface of the cover is made to represent rectangular moldings, increasing in height toward the raised rectangular center portion, b , of the top. Said representations of moldings are produced by a series of beads or rounded raised portions, $b' b^2 b^3 b^4 b^5$, successively increasing in height toward the raised center portion, b , and arranged in rectangular lines. We do not limit ourselves, however, to the precise number of said beads, since the general effect can obviously be produced by either a greater or a less number of such beads.

In conclusion, we may state that certain features of our design are represented in the mechanical patent, No. 379,522, granted to us March 13, 1888, upon an application therefor filed on or about January 23, 1888.

What we claim is—

In a design for a photograph-exhibitor case, the substantially half-oval-shaped body A and the cover B, having representations of moldings which rise in height from the edge toward the center of the cover, substantially as shown and described.

GEORGE M. PORTEOUS.
FREDERICK S. MILLER.
